CLAIM

I claim, the ornamental design for a luminaire, as shown and described.

DESCRIPTION

FIG. 1 is a first side plan view of a third embodiment of the invention;

FIG. 2 is a second side plan view of the embodiment of FIG. 1;

FIG. 3 is a bottom plan view of the embodiment of FIG. 1;

FIG. 4 is a top plan view of the embodiment of FIG. 1;

FIG. 5 is a top perspective view of the embodiment of FIG. 1;

FIG. 6 is a bottom perspective view of the embodiment of FIG. 1;

FIG. 7 is a first side plan view of a third embodiment of the invention;

FIG. 8 is a second side plan view of the embodiment of FIG. 7;

FIG. 9 is a bottom plan view of the embodiment of FIG. 7;

FIG. 10 is a top plan view of the embodiment of FIG. 7;

FIG. 11 is a top perspective view of the embodiment of FIG. 7; and,

FIG. 12 is a bottom perspective view of the embodiment of FIG. 7.

The degree of transparency or opaqueness of the lens of the luminaire forms no part of the claimed design, the lens of the claimed luminaire may have facets, lenslets or other treatments.

The phantom lines shown in FIG. 1-FIG. 12 are environmental and not part of the claimed design.

The color and shading of the luminaire forms no part of the claimed design, the luminaire according to the claimed design may be any color or combination of colors.

The surface treatment of the luminaire forms no part of the claimed design, the luminaire of the claimed design may have any surface treatment. References to "side", "top", "front" and "bottom" in the figure descriptions are not meant to require certain in-use orientation; a luminaire according to the claimed design may be used in any orientation.
